UNITED STATES PATENT OFFICE.

HARRY A. ROGERS, OF NIAGARA FALLS, NEW YORK.

DESIGN FOR A FINGER-RING BLANK.

SPECIFICATION forming part of Design No. 33,934, dated January 22, 1901.

Application filed December 22, 1900. Serial No. 40,823. Term of patent 3½ years.

To all whom it may concern:

Be it known that I, HARRY A. ROGERS, a citizen of the United States, residing at Niagara Falls, in the county of Niagara and State of New York, have invented and produced a new and useful Design for Finger-Ring Blanks, of which the following is a specification.

My invention relates to new and useful designs for finger-ring blanks; and the object of the same is to produce a device of attractive design which can be bent into the form of a finger-ring and so worn.

The following is a specification of my new design, reference being had to the accompanying drawings, forming a part thereof, in which—

Figure 1 is a plan view of my blank. Fig. 2 is a side elevation of the same.

Like numerals of reference designate like parts in both views of the drawings.

The numeral 1 designates the shank portion of my blank, which is uniformly beveled on the two sides 2 and the top 3 from one end to the other. A pyramidal point 4 is formed on one end of the shank 1 and a frusto-

pyramidal head 5 on the other. This combination of the shank 1, point 4, and head 5 has approximately the shape of a nail. On the outer face of the head 5 is formed a buffalo's head 6, cut off just back of the horns. 30 Panels 7 and 8 are formed on the top surface of the shank and head, respectively, on which names or dates may be placed.

The essential feature of my design is the nail-shaped shank portion uniformly beveled 35 on the two sides and top and surmounted by a frustum-pyramidal head bearing a buffalo's head on its outer face.

Having thus described my invention, what I claim as new, and wish to secure by Letters 40 Patent, is—

The design for a finger-ring blank, as herein shown and described.

In testimony whereof I have hereunto set my hand in presence of two subscribing witnesses.

HARRY A. ROGERS.
